(57) **CLAIM**

The ornamental design for a travel pillow, as shown and described herein.

DESCRIPTION

FIG. 1 is a top, front, right side perspective view of a travel pillow of the present invention.

FIG. 2 is a top, rear, left side perspective view of the travel pillow shown in FIG. 1.

FIG. 3 is a front elevation view of the travel pillow shown in FIG. 1.

FIG. 4 is a rear elevation view of the travel pillow shown in FIG. 1.

FIG. 5 is a left side elevation view of the travel pillow shown in FIG. 1.

FIG. 6 is a right side elevation view of the travel pillow shown in FIG. 1.

FIG. 7 is a top plan view of the travel pillow shown in FIG. 1.

FIG. 8 is a bottom plan view of the travel pillow shown in FIG. 1.

FIG. 9 is a top, front, right side perspective view of the travel pillow shown in FIG. 1, in a second configuration.

FIG. 10 is a top, rear, left side perspective view of the travel pillow shown in FIG. 1, in the second configuration shown by FIG. 9.

FIG. 11 is a front elevation view of the travel pillow shown in FIG. 1, in the second configuration shown by FIG. 9.

FIG. 12 is a rear elevation view of the travel pillow shown in FIG. 1, in the second configuration shown by FIG. 9.

FIG. 13 is a left side elevation view of the travel pillow shown in FIG. 1, in the second configuration shown by FIG. 9.

FIG. 14 is a right side elevation view of the travel pillow shown in FIG. 1, in the second configuration shown by FIG. 9.

FIG. 15 is a top plan view of the travel pillow shown in FIG. 1, in the second configuration shown by FIG. 9; and, FIG. 16 is a bottom plan view of the travel pillow shown in FIG. 1, in the second configuration shown by FIG. 9.

(Continued)

The broken lines in the drawings depict portions of the travel pillow that form no part of the claimed design.
